UNITED STATES PATENT OFFICE.

WILLIAM O. REW, OF MYERS, FLORIDA.

DESIGN FOR A FINDER ATTACHMENT FOR TROLLEY-POLES.

SPECIFICATION forming part of Design No. 29,709, dated November 22, 1898.

Application filed November 1, 1898. Serial No. 695,242. Term of patent 7 years.

To all whom it may concern:

Be it known that I, WILLIAM O. REW, a citizen of the United States, residing at Myers, in the county of Lee and State of Florida, have 5 invented and produced a new and original Design for a Finder Attachment for Trolley-Poles, of which the following is a specification.

This invention relates to a new and original o design for a finder attachment for trolley-poles; and it has for its object to provide a design of this character which shall be both useful and ornamental.

The leading feature of the design resides in 5 a wire-finder for trolley-poles formed with a body having at one end an approximately straight stem and beyond said stem being longitudinally bifurcated and provided with opposite parallel circular ear portions adjoining o the stem and with opposite duplicate guide-arms diverging from the edges of the circular ears and disposed at an obtuse angle to the stem, said guide-arms also having a slight longitudinal curvature.

5 The foregoing constitute the leading or characteristic features of the design, and the minor features of the design may be stated to be the stem having a slight longitudinal curvature and flaring into the circular ear o portions, as well as being provided at its terminal with an eye or loop.

Another minor feature of the design is a body having inwardly-pointing shoulder projections at the junction between the diverging arms and the edges of the circular ears.

In the drawings, Figure 1 is a front view of a finder attachment for trolley-poles embodying the herein-described design. Fig. 2 is a side elevation thereof.

Referring to the drawings, the numeral 1 40 designates the body of the finder attachment, which is designed for guiding a trolley-wheel into contact with a trolley-wire, and said body is provided at one end with a stem 2, having a slight longitudinal curvature and provided 45 at its terminal with a circular loop or eye 3. Beyond the stem 2 the body 1 is longitudinally bifurcated and provided with opposite parallel circular ears 4, and opposite its terminal eye or loop 3 the stem 2 flares at the 50 point 5 into the circular ears 4. In addition to the circular ears 4 the bifurcated body 1 is provided with the opposite duplicate guide-arms 6, diverging on straight lines from the edges of the circular ears 4, but having a 55 slight longitudinal curvature. At the junction between the diverging arms and the edges of the circular ears the body 1 is provided with inwardly-pointing shoulder projections 7. 60

What is claimed is—

The design for a finder attachment for trolley-poles, herein shown and described.

In testimony that I claim the foregoing as my own I have hereto affixed my signature in 65 the presence of two witnesses.

WILLIAM O. REW.
